R. T. POLLOCK

APPARATUS FOR CONVERTING HYDROCARBON OILS

Filed Feb. 16, 1920

UNITED STATES PATENT OFFICE.

ROBERT T. POLLOCK, OF BOSTON, MASSACHUSETTS, ASSIGNOR TO UNIVERSAL OIL PRODUCTS COMPANY, OF CHICAGO, ILLINOIS, A CORPORATION OF SOUTH DAKOTA.

APPARATUS FOR CONVERTING HYDROCARBON OILS.

Application filed February 16, 1920. Serial No. 358,900.

To all whom it may concern:

Be it known that I, ROBERT T. POLLOCK, a citizen of the United States, residing in the city of Boston, county of Suffolk, and State of Massachusetts, have invented certain new and useful Improvements in Apparatus for Converting Hydrocarbon Oils, of which the following is a specification.

My invention relates to improvements in an apparatus for converting hydrocarbon oils and relates more particularly to an apparatus for separating the heavier from the lighter oils after the cracking of the oils.

Among the salient objects of this invention are to provide an expansion chamber which furnishes a large expansion area and one which quickly lessens the velocity of the gaseous vapor, thereby permitting the heavy oils to condense and collect therein; to provide a single expansion chamber of a size that will permit the collecting of a considerable quantity of heavy residuum which will supply a liquid for retaining in suspension the precipitated fixed carbon instead of its being deposited in a relatively dry state upon the inner surface of the expansion chamber, a factor of importance in the cleaning of the expansion chamber; to provide a collecting reservoir in which considerable quantities of gases and vapor may accumulate, and one from which the lighter condensable gases passing off to the condenser will be more uniform in character; to provide a single expansion chamber or reservoir which is easily cleaned, and in general to provide an apparatus of the character referred to.

In the drawings:

Fig. 1 is a side view of the expansion chamber showing inlet and drawoff leads with parts broken away.

Fig. 2 is an end view of the construction shown in Fig. 1.

Referring to the drawings, I have shown in detail two views of an expansion chamber which is to be interposed in the vapor line of an oil still. This vapor chamber may be used in combination with any type of still where the hydrocarbon oils are heated to a cracking temperature, directed to an expansion zone in which a portion of the cracked hydrocarbons are condensed and the vapors passed on from this expansion zone to a suitable condenser. I have purposely omitted the furnace with its cracking zone and condensing means, in view of the fact that they

may be of any usual type and are well known in the art.

The cracked hydrocarbon oils consisting of a body of hot oil, together with gaseous vapors enter the expansion chamber 1 through the inlet pipe 2. It will be noted that the expansion chamber is slightly inclined from the horizontal against the course of the oil and gaseous vapors, thereby furnishing a liquid trap in which the heavier oils collect at the bottom thereof, the upper part of the chamber being filled with the gaseous vapors. A drawoff pipe 3 controlled by a valve 4 supplies the means of drawing off this residuum from time to time. Together with this residuum which stands in the expansion tube is precipitated from time to time, a quantity of fixed carbon which is held in suspension in the heavy residuum. The fact that there is a considerable quantity of residual oil at all times in the expansion chamber reduces to a minimum the possibility of the fixed carbon which is precipitated in the cracking process from settling upon the inner surface of the expansion chamber. This is a very important factor, as the collection of carbon within the expansion zone of oil stills, produces numerous difficulties. Most important among these are the reduction of the cracking taking place in the oil, the absorption of heat and the clogging of the expansion tubes and vapor lines.

At either end of the chamber are supplied two cleaning plates 5 and 6 which are readily removable and open a large aperture in either end of the chamber, furnishing an easy means of cleaning the interior. The gaseous vapors rise through the vapor line 7 through the connection 8 and to the condensing zone through the line 9. A secondary drawoff pipe 10 returns any condensate which may collect in this line to the cracking tubes to be treated again. A plate 11 plugs the opposite end of the connection from that through which the vapor line 7 enters and may be removed when the line is to be cleaned.

The advantages of this construction are, first, the collecting of a considerable quantity of the residual oils in combination with the condensable and incondensable oil vapors, directly after they leave the cracking zone, thus producing a more uniform vapor to be subsequently condensed; secondly, the collecting of a considerable quantity of the

residual oil in one reservoir which holds in suspension the precipitated carbon. This, together with the quick and accessible cleaning features, combine a very efficient construction and one which may be readily adapted to any type of still.

I claim as my invention:

1. An expansion chamber of the character described, comprising an inclined elongated vapor chamber, an inlet pipe leading thereto near one end for introducing oil at a cracking temperature to said chamber, a residuum drawoff pipe leading from the vapor chamber, a vapor outlet from said chamber said residuum drawoff pipe and vapor outlet leading from said chamber at the opposite end of said chamber to the inlet pipe, the condensable gases and precipitated carbon accumulating in said chamber flowing into the inclined end thereof and being of its greatest depth adjacent the oil inlet, and being removed through said residuum discharge pipe at the opposite end of said chamber.
2. An expansion chamber, comprising an elongated expansion receptacle occupying

a longitudinal inclined position, means for feeding oil to said chamber at its inclined end, a vapor discharge from said chamber at the opposite end thereof, a residuum discharge from the chamber leading from the lower part thereof adjacent the vapor outlet, said chamber being adapted to retain unvaporized residue consisting of liquid oil and precipitated carbon contained therein, said residue being of its greatest depth adjacent the oil inlet to the chamber.

3. An expansion chamber of the character described, comprising an elongated vessel longitudinally inclined whereby one end occupies a position substantially lower than the other end thereof, means for introducing oil to the lower end of said chamber, vapor and residuum discharges from the opposite end thereof, said chamber being adapted to hold unvaporized residue containing precipitated carbon of a greater depth at the lower end of the chamber than at the residuum discharge.

ROBERT T. POLLOCK.
